Primary Examiner — Richard E Chilcot

(57) **CLAIM**

The ornamental design for a motorcycle helmet, as shown and described.

DESCRIPTION

The file of this patent contains at least one drawing/photograph executed in color. Copies of this patent with color drawings/photographs will be provided by the Office upon request and payment of the necessary fee.

1. Motorcycle helmet

FIGURE 1.1 is a rear view of a motorcycle helmet showing my design.

FIGURE 1.2 is a bottom view thereof;

FIGURE 1.3 is a top view thereof;

FIGURE 1.4 is a front view thereof;

FIGURE 1.5 is a perspective view thereof;

FIGURE 1.6 is a side view thereof;

FIGURE 1.7 is an opposite side view thereof;

FIGURE 1.8 is an exploded front view thereof; and

FIGURE 1.9 is an exploded perspective view thereof.
